VENTILATOR

Roland M. Purdy, Bainbridge, N.Y., assignor to
 Bendix Aviation Corporation, New York, N.Y., a corporation of Delaware

Application May 1, 1946, Serial No. 666,359

9 Claims. (Cl. 98-1)

1

This invention relates to a ventilator. The invention is adapted to many uses, but will be described in particular relation to a small ventilator of the type employed to exhaust small electrical machinery, it being understood that this particular description is not limitative but is for purposes of illustration only.

Two general types of ventilator are described in the prior art. The earlier of these types has a discharge pipe connecting the space that is to be ventilated to a swinging head controlled by a wind vane that turns the back of the ventilator to the wind which draws the air from within the ventilator pipe in passing. That type of ventilator has recognized faults, among which are its tendencies under certain conditions to admit rainwater and to provide down drafts.

In order to overcome the objections to ventilators of the swinging head type, it has been proposed to use fixed ventilators having a maze of baffles intended to permit unidirectional, outward flow of air only. For some uses, the fixed type of ventilator is superior to the swinging head type, but the fixed type has its faults also. The draft is not always good, stray currents appear to wander between the inner and the outer chambers and to lower the efficiency of the device, and the exclusion of rain or other liquids is not always accomplished when the device is employed in exposed positions.

It is an object of this invention to provide a stationary ventilator with improved draft and decreased back draft.

Another object of the invention is to provide a ventilator of improved design and construction which can be made, by methods offering the greatest manufacturing advantages, in shapes adapted to produce the most efficient results.

Another object of the invention is to accomplish the objects of the invention by a ventilator having at least three concentric slotted chambers, the slots of which are offset with respect to each other.

Another object of the invention is to employ the principles of the Venturi tube in a fixed ventilator to increase the draft thereof.

Other objects of the invention will be in part apparent and in part described in the specification which follows.

The above and further objects and novel features of the invention will more fully appear from the following detailed description when the same is read in connection with the accompanying drawings. It is to be understood, however, that the drawings are for the purpose of illustration

only, and are not intended as a definition of the limits of the invention, reference for this latter purpose being had primarily to the appended claims.

5 In the drawings, wherein like reference characters refer to like parts throughout the several views.

Fig. 1 is a vertical section through an exemplary ventilator substantially on the line 1—1 of Fig. 2;

Fig. 2 is a cross-section substantially on the line 2—2 of Fig. 1;

Fig. 3 is an elevational view of a ventilator head constructed in accordance with the principles of this invention;

Figs. 4, 5, and 6 are perspective views of the three caps or shells that are adapted to fit the head of Fig. 3; and

Fig. 7 is a vertical cross-section through a modified form of the invention.

In the preferred form of the invention, which is disclosed in Figs. 1 to 6, the numeral 10 indicates in general a ventilator head which has a screw threaded shank 11, and an annular flange 12 upon which are formed a series of annular steps 13, 14, 15, 16. The bore 17 of the head terminates short of the top and is connected with the discharge openings 18, which are shown in this modification to be four in number normal to the bore and to the openings on either side. The top of the head is provided with a shoulder 19 and a stud 20 which cooperate with the annular steps to seat the caps that form the chambers and produce the draft.

35 The inner chamber, which is designed to receive the discharge from the openings 18 is formed by the cap 21 which has a central opening that fits the stud 20, as shown in Fig. 1, and is provided in its side with slots 22 that permit its gas content to be drawn into the chamber formed by cap 23. The walls of the cap 21 are of such length and diameter that they rest upon the step 15 and snugly fit the annular side of the step 16 when the cap is seated upon the shoulder 19.

45 The intermediate cap 23 is dimensionally larger but is similar to the cap 21, except that its slits are provided with out-turned flanges 24 which extend throughout the height thereof and deflect moving gases past the openings in such a manner that the gases within the chamber formed by caps 21 and 23 are drawn therefrom. This provision of a baffle between the suction cap 23 and the discharge openings 18 is of great advantage because it reduces the turbulence about 50 the discharge openings caused by vagrant gas

currents, and produces an improved and a steadier draft. The cap 23 preferably has a snug fit to the top of cap 21, the exterior of step 15, and the top of step 14.

In order to complete the device and to produce therewith a maximum draft, there is provided an outer cap 25 which seats upon the ledge 13 and snugly against the annular face of ledge 14. When the three caps are in concentric position as shown in Fig. 1, the stud 20 may be headed to provide a permanent uniting of the parts.

The outer shell has openings thereabout, at least one of which is bound to receive air or other gas currents from whatever side the air blows, others of which serve as discharge ports for such currents and for the gas exhausted through the ventilator head. The currents of gas are shown, in Fig. 2, to be coming from the direction which, on a compass rose, would be northwest. They enter directly into that slot of the cap and are diverted as shown by the arrows toward the adjacent flanges in the intermediate cap 23. The flanges extend toward the outer wall of the ventilator, reduce the area of the passage which the gases follow, and produce a Venturi effect of increased velocity and decreased pressure past the openings, thereby acting with increased effect to exhaust the air from within the next inner chamber. The exhausting and exhausted gases escape through the next openings in the outer wall, as shown by the arrows.

The step construction of the flange 12 is of great advantage in preventing the access of moisture to the interior of the ventilator and in maintaining drainage. However, the step construction need not necessarily be employed.

The caps may be most simply made from flat blanks of suitable metal such as aluminum; a satisfactory method includes stamping out and bending to the required shape. The stamping of the intermediate cap shown in Fig. 5 is preferably so executed as to produce in one operation the flanges 24. The area of the openings in the successive caps preferably increases outwardly, to produce the greatest draft possible within the limiting size of the unit.

It is not necessary to permanently connect the caps to the head but they may be temporarily connected thereto as shown in Fig. 7. In that figure, the ventilator head 30 has a flange 35 with only two steps 31, 32. The outer cap 33 is provided with slits 34 and encircles the flange 35, preferably resting snugly thereagainst during operation. A cylindrical member 36 having an annular flange 37 is emplaced within the member 33 with the flange bearing against the inner surface thereof. Within the member 36 is another cylindrical member 38 having slits 39 and an annular flange 40 which rests upon the step 31. The ventilator is assembled by means of a screw 42 which is threaded into the upper portion 43 of the head 30. A washer and lock washer are shown between the cap 33 and the head of the screw.

In Figs. 1 to 6 there are four openings or slits, such as at 22, in each cap and four openings 18 in the head 10. The openings 22 in the inner cap are offset 45° from the discharge openings 18, the openings in the intermediate cap 23 are offset 45° from those of the inner cap, and the openings of the outer cap are offset 45° from those of the intermediate cap. This arrangement is automatically assured by small studs 50, 51, 52 mounted on and extending upwardly from flange 12 in the circles of the caps, each said stud extend-

ing into the open end of a slit in one of the caps. However, it is to be understood that while this arrangement is preferred, other degrees of offset could be employed and a greater or lesser number of slits arranged in the several caps. In Fig. 7, for example, the openings in particular caps are not arranged diametrically.

These ventilators are of exceptional efficiency, inexpensive to construct, easy to assemble and dismantle, and pleasing in appearance. They may be made in sizes far smaller than that illustrated in the drawings and in very large sizes, and exhibit superior efficiency in each size. They are practically waterproof and are practically proof against back drafts even under the most adverse conditions.

Although only two embodiments of the present invention have been illustrated and described in the accompanying drawings and specification, it is to be expressly understood that the invention is not limited to said embodiments. Various changes may be made therein, particularly in the design and arrangement of the parts illustrated, and in the material used, without departing from the spirit and scope of the invention, as will now be apparent to those skilled in the art. For a definition of the limits of the invention, reference is had primarily to the appended claims.

What is claimed is:

1. A ventilator comprising an air discharge head having a bore, a discharge opening normal thereto, an axially arranged stud and a flange with a series of annular steps, three concentric cylindrical caps aligned by the stud and conforming to the steps, slots dividing said caps into sections, cooperable means on the head and caps to position the same and circumferentially offset the slots in the intermediate cap from those in the other caps, and out-turned flanges along the slot edges of the intermediate cap.

2. A ventilator comprising an air discharge head having a bore, discharge openings normal thereto, a stud at the end thereof and a flange with a series of annular steps, three concentric cylindrical caps conforming to the steps and aligned by the stud, slots dividing said caps into quadrants, means on the flange to position the slots in adjacent caps at 45° to each other, and out-turned flanges along the slot edges of the intermediate cap.

3. A ventilator comprising a central discharge head having an axial bore terminating intermediate its ends and port means connecting the inner end of the bore and the external surface of the head, an external flange on said head, means comprising a plurality of cylinders seated against said flange around said port means and forming the walls of a plurality of concentric annular chambers around a portion of said head, said port means being spaced from both ends of the innermost chamber and each of said walls being axially slotted to connect adjacent chambers to each other, the slots in each wall being circumferentially offset with respect to the slots in adjacent walls, flange means on each of said cylinders forming the end walls of said chambers opposite said head flange, means connected with said head and extending centrally through and operatively engaging said flange means for securing said head and chamber forming means in fixed relation to each other, and outwardly curved flanges along the edges of the slots in at least one of said walls.

4. A ventilator comprising a central discharge head having an axial bore and port means con-

necting said bore and the external surface of the head, means comprising a plurality of concentric cylinders surrounding said port means and forming the walls of a plurality of concentric annular chambers around a portion of said head, said port means being spaced from both ends of the innermost chamber and each of said walls being axially slotted to connect adjacent chambers to each other, external flange means on said head forming an end wall of said chambers, internal flange means on at least one of said cylinders forming the other end wall of said chambers, and means connected with said head for securing said internal flange means to the head.

5. A ventilator comprising a central discharge head having a bore and discharge port means connecting said bore with the external atmosphere, external flange means on said head, means seated against said flange means around said port means and forming a plurality of concentric annular chambers around a portion of said head, said last-named means including radially spaced concentric side walls and internal flange means on at least one of said side walls forming the ends of said chambers opposite said external flange means, and means extending centrally through said internal flange means for securing said internal flange means to said head, said port means being spaced from said external flange means and said side walls having axially extending slots for connecting adjacent chambers.

6. A ventilator comprising a central discharge head having an axial bore and radially extending port means connecting said bore and the external surface of the head, means surrounding said port means and forming a plurality of concentric annular chambers around a portion of said head, said means comprising a plurality of concentric cylinders forming the side walls of said chambers, and external flange means on said head and

internal flange means on at least one of said cylinders forming the end walls of said chambers, said port means being spaced from said external flange means, and means extending centrally through and connecting said internal flange means to said head, said side walls having circumferentially spaced slots therein for connecting said chambers, the slots in adjacent walls being circumferentially offset with respect to each other.

10 7. A ventilator as defined in claim 6 wherein outwardly curved flanges are provided along the edges of the slots in at least one of the intermediate side walls.

15 8. A ventilator as defined in claim 6 wherein the surface of said external flange means forming the end walls of said chambers has a general contour which is inclined to the longitudinal axis of said bore.

20 9. A ventilator as defined in claim 8 wherein said head flange surface is stepped, the steps serving as pilots for said chamber forming means.
